(57) **CLAIM**

I claim the ornamental design for a golf putter grip, as shown and described.

DESCRIPTION

FIG. 1: shows a perspective front, top and right side view of a golf putter grip showing the design;

FIG. 2: shows a front elevational view of the golf putter grip of FIG. 1;

FIG. 3: shows a right side elevational view of the golf putter grip of FIG. 1;

FIG. 4: shows a rear elevational view of the golf putter grip of FIG. 1;

FIG. 5: shows a left side elevational view of the golf putter grip of FIG. 1;

FIG. 6: shows a top plan view of the golf putter grip of FIG. 1;

FIG. 7: shows a bottom plan view of the golf putter grip of FIG. 1;

FIG. 8 shows a perspective front, top and right side view of a second embodiment of the a golf putter grip;

FIG. 9: shows a front elevational view of the golf putter grip of FIG. 8;

FIG. 10: shows a right side elevational view of the golf putter grip of FIG. 8;

FIG. 11: shows a rear elevational view of the golf putter grip of FIG. 8;

FIG. 12: shows a left side elevational view of the golf putter grip of FIG. 8;

FIG. 13: shows a top plan view of the golf putter grip of FIG. 8;

FIG. 14: shows a bottom plan view of the golf putter grip of FIG. 8;

FIG. 15 shows an enlarged perspective front, top and right side view of the a golf putter grip of FIG. 1;

FIG. 16: shows a front elevational view of the golf putter grip of FIG. 15;

FIG. 17: shows a right side elevational view of the golf putter grip of FIG. 15;

FIG. 18: shows a rear elevational view of the golf putter grip of FIG. 15;

FIG. 19: shows a left side elevational view of the golf putter grip of FIG. 15;

FIG. 20: shows a top plan view of the golf putter grip of FIG. 15; and,

FIG. 21: shows a bottom plan view of the golf putter grip of FIG. 15.

The broken lines shown in FIGS. 1 to 21 are included for the purpose of showing the environment, and form no part of the claimed design.

1 Claim, 6 Drawing Sheets
